UNITED STATES PATENT OFFICE.

ARCHER G. JONES, OF RICHMOND, VIRGINIA.

DESIGN FOR A BADGE, BUTTON, OR EMBLEM.

56,617.

Specification for Design.

Patented Nov. 16, 1920.

Application filed March 7, 1919. Serial No. 281,311. Term of patent 14 years.

To all whom it may concern:

Be it known that I, ARCHER G. JONES, a citizen of the United States, residing at Richmond, in the county of Henrico and State of Virginia, have invented a new, original, and ornamental Design for Badges, Buttons, and Emblems, of which the following is a specification, reference being had to the accompanying drawing, forming a part thereof.

The figure is a plan view of the badge, button, or emblem showing my new design.

I claim:

The ornamental design for a badge, button, or emblem, as shown.

ARCHER G. JONES.
